(57) **CLAIM**

We claim the ornamental design for a kettle, as shown and described.

DESCRIPTION

FIG. 1 is a perspective view of a kettle showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top elevational view thereof; and,

FIG. 7 is a bottom elevational view thereof.

The broken lines in the drawings are included for the purpose of illustration and form no part of the claimed design.
